APPARATUS FOR HEAT TRANSFER

Henry A. Burggrabe and William K. Body, Detroit, Mich., assignors to Borg-Warner Corporation, Chicago, Ill., a corporation of Illinois

Application April 9, 1938, Serial No. 201,040

1 Claim. (Cl. 62—115)

This invention relates to a method of and apparatus for heat transfer and, as illustrated in the drawings, has particular reference to the art of refrigeration.

The invention as illustrated in the embodiment selected for purposes of illustration contemplates a refrigerating system including a compressor, a condenser adapted to receive refrigerant discharged by the compressor, a motor for driving said compressor and means for conducting refrigerant from the condenser in heat exchange relationship with the motor for dissipating heat therefrom.

A principal object of the invention is to provide a new and improved method of and apparatus for heat transfer, particularly in connection with a refrigerating system.

Another object of the invention is to provide a new and improved method of and apparatus for dissipating heat from a refrigerating system and from the source of energy which effects the operation of such system.

Another object of the invention is to provide a new and improved method of and apparatus for dissipating heat from an electric motor which operates to drive a compressor of a refrigerating system.

Another object of the invention is to provide a new and improved method of and apparatus for heat transfer useful in refrigerating systems of the compressor type whereby the efficiency of the heat dissipating elements and parts of the system is increased and the possible capacity of the system as a whole is increased.

Another object of the invention is to provide a new and improved refrigerating system which includes a sealed unit construction with means for efficiently dissipating heat from the sealed unit.

Another object of the invention is to provide a new and improved construction for refrigerating systems of the sealed unit type, which is cheaper in construction and more efficient in operation than refrigerating systems of the sealed unit type now commonly employed.

Other objects and advantages of the invention will be apparent from a consideration of the following specification taken in conjunction with the accompanying drawings of which there are two sheets and wherein

Fig. 1 is an illustration of a refrigerating system embodying the invention;

Fig. 2 is a plan view of the condensing unit part of the refrigerating apparatus illustrated in Fig. 1;

Fig. 3 is an enlarged elevational view of the

condensing unit part of the system illustrated in Fig. 1; and

Fig. 4 is a vertical sectional view of the sealed unit or motor compressor unit such as appears from a view taken in a plane on the line 4—4 of Fig. 2 looking in the direction of the arrows.

Referring now to Fig. 1 of the drawings, there is shown a refrigerating system of the compressor, condenser, expander type and which includes a sealed motor compressor unit 10, a condenser 12, an evaporator 14 and a thermostatic control switch 16 arranged in the motor circuit 18 and having a thermal element 20 associated with the evaporator 14 so that the motor compressor unit 10 will operate to supply refrigerant to the evaporator 14 in accordance with the pre-selected temperature requirements thereof. The evaporator 14 is illustrated as being arranged within a heat insulated compartment 21, and a liquid line 22 connected with the liquid receiver 24 of the condensing unit is adapted to supply liquid refrigerant to the evaporator under the control of some suitable control, such as a low side or high side float control, and a suction line 26 is connected to the evaporator 14 for returning vaporous refrigerant therefrom to the motor compressor unit 10.

The condensing unit, which is illustrated in Figs. 2 and 3, includes the motor compressor unit 10, the condenser 12 and the liquid receiver 24.

The motor compressor unit 10 comprises a sealed casing 28 wherein there is arranged an electric motor 30 and a refrigerant compressor indicated generally at 32 and which compressor is driven by the motor 30. Vaporous refrigerant from the evaporator is delivered by the suction line 26 to the intake side of the compressor 32 and such refrigerant after being compressed by the compressor is discharged into the space within the shell 28 of the motor compressor unit 10. From the shell 28 refrigerant under the discharge pressure of the compressor 32 is conducted by the conduit 34 to the condenser 12. The condenser 12 generally comprises a pair of side frame members 36 which form a support for the finned coils 38 and which finned coils are adapted to be exposed to air so as to dissipate heat from the refrigerant within the coils. The condenser 12 consists of two parts which may be called a primary condenser 40 and a secondary condenser 42.

The vaporous refrigerant from the motor compressor unit 10 is conducted by the conduit 34 to one end 44 of the primary condenser 40 and the other end 46 of the primary condenser is connected by a conduit 48 to an annular jacket or

chamber 50 disposed around the motor 30 of the motor compressor unit 10. A conduit 52 is provided for conducting refrigerant from the jacket 50 to one end 54 of the secondary condenser 42 and a conduit 56 is provided for conducting refrigerant from the other end 58 of the secondary condenser 42 to the liquid receiver 24. The liquid line 22 is connected to the liquid receiver 24 for supplying liquid refrigerant therefrom to the evaporator 14.

The shell 28 of the motor compressor unit 10 may consist, as illustrated, of two drawings 27 and 29 which are welded together so as to form a gas-tight shell in which the motor 30 and the compressor 32 are arranged. The conduit 26 which conducts refrigerant to the compressor 32 and the conduit 34 which conducts refrigerant from within the casing 28 to the condenser passes through the walls of the casing 28 and are sealed so as to prevent loss of gas therearound. Leads 60 may be mounted in the top of the casing 28 by means of which current may be supplied to the windings of the motor 30. The motor 30 may be a split-phase motor having starting and running windings, in which event three leads, as illustrated in Fig. 2, would be required. The compressor 32 and the motor 30, which are directly connected, may be supported within the casing 28 by means of a sleeve 62 press-fitted into the casing 28 and the walls of the casing 28 opposite the sleeve 62 may be bulged outwardly, as illustrated, to form the jacket 50. The motor compressor unit is further described and claimed in the copending application of John C. Buchanan et al., filed May 25, 1938, Serial No. 209,914, for Refrigeration, and reference may be had to such application for further details of the construction and operation of the motor compressor unit per se. The unit 10 may be provided with several brackets 64 by means of which the unit 10 can be suspended from brackets 66 carried by a frame 68 mounted on the condenser, springs 70 being employed for suspending the unit 10 from the brackets 66 so as to prevent the transmission of vibration from the unit 10 to the condenser 12. The conduits connecting the unit 10 with the condenser 12 and the evaporator 14 may be formed of copper tubing and be sufficiently flexible to prevent the transmission of vibration by means of the conduits to other parts of the system. The frame 68 may comprise several pieces of strip metal bent and secured together and bolted to the side frame members 36 of the condenser so that the motor compressor unit will be supported in a vertical position above the condenser as illustrated. The receiver 24 may likewise, as illustrated, be carried by a part of the frame 68.

The first stage or pass 40 of the condenser 12 may be of such capacity that the conduit 48 will deliver to the jacket 50 approximately just sufficient liquid refrigerant so as to keep the temperature of the motor 30 within a desired working range under the various temperature and pressure conditions to which the system is subjected. In other words, the first pass 40 of the condenser may be of such capacity that the refrigerant leaving the jacket through the conduit 52 will

all be in a vaporous state and will be delivered to the second pass or stage 42 of the condenser. This second stage or pass of the condenser is of sufficient capacity to liquify all of the refrigerant under the various conditions of temperature and pressure for which the system has been designed. By increasing or decreasing the capacity of the first pass 40 of the condenser, the temperature at which the motor operates may be varied. It is possible with this type of construction to rather accurately control the temperature of the motor under its various conditions of operation. The liquid refrigerant delivered by the conduit 48 to the jacket 50 functions to absorb heat from the motor windings, as a result whereof temperature of the motor is reduced or regulated and this motor heat which is added to the liquid refrigerant will vaporize the same and will be dissipated from the refrigerant in the second pass of the condenser.

This system of dissipating heat from the motor compressor unit 10 serves to increase the efficiency of the system as a whole, and actually increases the capacity of the system. This method of dissipating heat from the motor compressor unit also is somewhat less expensive than fins which have heretofore been employed on motor compressor units. If desired the size of the jacket 50 may be increased or decreased for changing the rate at which heat may be dissipated from the motor compressor unit 10.

The particular details of construction of the various pieces of apparatus illustrated are not particularly important to the invention and it is to be understood that various changes in design, size, shape and form may be made in the system and the parts thereof without departing from the scope of the invention as defined in the following claim.

40 While the invention has been described with some detail, it is to be understood that the description is for the purpose of illustration only and is not definitive of the limits of the inventive idea. The right is reserved to make such 45 changes in the details of construction and arrangement of parts as will fall within the purview of the attached claim.

We claim:

50 A refrigerating apparatus including a sealed casing having a motor section and a compressor section, said motor section being pressed out at the side thereof to define a channel, an annular sleeve pressed into said motor section and forming with said channel an annular passage between said sleeve and said motor section, motor 55 windings supported within said annular sleeve, a frame connected with the bottom of said annular sleeve, a compressor unit supported upon said frame independently of the compressor section of said sealed casing and arranged to be driven by said motor, said annular passage being arranged for circulation therethrough of a refrigerant for effecting indirect heat exchange with said motor for removing heat therefrom.

60 HENRY A. BURGGRABE.
